UNITED STATES PATENT OFFICE.

ERNST KARG, OF NEW YORK, N. Y.

DESIGN FOR A DOLL.

47,599.

Specification for Design.

Patented July 20, 1915.

Application filed April 9, 1915. Serial No. 20,352. Term of patent 3½ years.

To all whom it may concern:

Be it known that I, ERNST KARG, a subject of the Emperor of Germany, residing at New York, in the county of New York and State of New York, have invented a new, original, and ornamental Design for Dolls, of which the following is a specification, reference being had to the accompanying drawing, forming part thereof.

The figure is a front view of a doll illustrating my new design.

I claim:

The ornamental design for a doll, as shown.

ERNST KARG.

Witnesses:

Wm. I. COHEN,
MINNIE S. MILLER.
